UNITED STATES PATENT OFFICE.

WALTER LYTTON, OF CHICAGO, ILLINOIS.

DESIGN FOR A RADIOCABINET.

Application filed October 14, 1922. Serial No. 3,977. Term of patent 3½ years.

To all whom it may concern:

Be it known that I, WALTER LYTTON, a citizen of the United States, residing at Chicago, in the county of Cook and State of Illinois, have invented a new, original, and ornamental Design for Radiocabinets, of which the following is a specification, reference being had to the accompanying drawing, forming a part thereof.

The Figs. 1 and 2 are respectively a front and side elevation of the cabinet open, as I consider the inside appearance of the cabinet as a material part of the invention.

I claim:

The ornamental design for a radiocabinet, as shown.

WALTER LYTTON.
